UNITED STATES PATENT OFFICE.

EMANUEL HIPPARD, OF YOUNGSTOWN, OHIO..

TRANSOM-LIFTER.

SPECIFICATION forming part of Letters Patent No. 417,182, dated December 10, 1889.

Application filed October 23, 1889. Serial No. 327,887. (No model.)

To all whom it may concern:

Be it known that I, EMANUEL HIPPARD, a citizen of the United States, residing at Youngstown, in the county of Mahoning and State of Ohio, have invented certain new and useful Improvements in Sash-Operators for Greenhouses; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to certain new and useful improvements in means for opening and shutting the sash of greenhouses and other like structures, which improvements will be fully understood from the following description, when taken in connection with the accompanying drawings, in which—

Figure 1 is a perspective view in detail of a sash-operator, showing the sash closed. Fig. 2 is a perspective showing a modification of the device, and Fig. 3 is a horizontal section of the gear and worm.

Referring by letter to the accompanying drawings, A designates a standard composed of two sections 1 and 2 of tubing or pipe, 30 which rises perpendicularly from the floor of the greenhouse to the glazed roof thereof, and is rigidly secured to the under side of said roof in the desired position by means of a short T-arm 4, the stem of which is pivoted 35 in the bifurcated head 3, bolted to the upper end of the casting or bracket B, secured to the upper end of the upper section 2 of the tubing. Below the extension 4, on the upper end of the bracket B, is a box or bearing 5 for 40 the horizontal line-shaft F', which is also journaled in suitable hangers depending from the roof-framing. Said line-shaft F' is provided with a miter-gear H, which is keyed 45 thereto and engages a miter-pinion d' at the upper end of a vertical-shaft section 2 of the standard A, the upper end of the lower section 1 of the standard being provided with a cog-gear E, which is engaged by a worm on the shaft b, seated in ears a, cast with the 50 sleeve of the bracket G, which sleeve binds

the sections of tubing together. The shaft b is provided with a hand-wheel D, provided with a handle by which to turn it.

M designates an arm, which is secured rigidly to the free end of a sash L and provided at its inner end with an upturned curve, to which latter is attached one end of a cord or wire p, the other end of which latter is attached to the line-shaft F' and wound thereupon in the direction shown in Fig. 2. To the lower horizontal rail of the sash and in close relation to the arm M, I attach one end of another cord or wire p', the other end of which is attached to and wound upon the line-shaft F' in a direction opposed to the winding of the cord or wire p on the shaft and on the opposite side of a dividing-collar N, secured to this shaft by a set-screw n.

In lieu of the cords or wires above described, I represent in Fig. 1, which I deem a fair modification of the said parts, an arm M', which is rigidly secured to the line-shaft F' and pivoted at its inner curved end to the inner end of the arm M. In this modification there is a positive connection between the motive power and the sash, while in the first instance, above described, the connections are flexible.

It will be observed from the foregoing that I transmit by direct positive movements rotation to the line-shaft through the medium of a vertical shaft, on the lower end of which is the self-locking worm-screw, and on the upper end of which is the bevel-pinion meshing with a bevel gear-wheel on the line-shaft; 80 also that, in case of Fig. 1, I flexibly connect the window-sash to the line-shaft, so that there is no liability of injurious shock or concussion in the act of opening and closing the sash.

Having thus fully described my invention, what I claim as new, and desire to secure by Letters Patent, is—

1. The combination, in a sash-operator for greenhouses, of the sectional standard provided with a bracket having a pivoted adjustable T-arm at its upper end, the horizontal screw provided with a hand-wheel journaled in a bracket connecting the sections of the standard, a vertical shaft within the up- 95 100

per section of the standard provided at its upper end with a pinion and at its lower end with a worm-wheel engaging a screw, a line-shaft provided with a gear-wheel engaging the upper pinion, and means, substantially as described, for connecting the line-shaft with the window-sash, substantially as specified.

2. The combination of the sectional standard provided with brackets, as described, the worm-screw horizontally arranged and provided with a hand-wheel, the vertical shaft

geared to the line-shaft, the arm M', rigidly secured to this shaft, and the arm M, rigidly secured to the free end of the sash and pivoted to the arm M', all substantially as described. 15

In testimony whereof I affix my signature in presence of two witnesses.

EMANUEL HIPPARD.
